UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,268,953.

Specification of Letters Patent. Patented June 11, 1918.

Application filed October 25, 1917. Serial No. 198,479.

To all whom it may concern:

Be it known that we, JOHN R. FLANNERY and ETHAN I. DODDS, citizens of the United States, and residents of Pittsburgh, in the 5 county of Allegheny and State of Pennsylvania, have invented certain new and useful Improvements in Stay-Bolt Structures; and we do hereby declare the following to be a full, clear, and exact description of the 10 invention, such as will enable others skilled in the art to which it appertains to make and use the same.

This invention relates to improvements in staybolt structures and more particularly to means for denoting the condition of integrity of staybolts for boilers,—the object of the invention being to provide simple and efficient means whereby the condition of the bolt may be ascertained without removing the same or any part thereof from the boiler and to so construct and arrange such means that the desired information may be obtained by audible signal means within the staybolt.

25 With this object in view the invention consists in certain novel features of construction and combinations of parts as hereinafter set forth and pointed out in the claims.

30 In the accompanying drawings, Figure 1 is a view illustrating an embodiment of our invention. Fig. 2 is a sectional view on the line 2—2 of Fig. 1, and Fig. 3 is a view showing a slight modification.

35 1 represents a staybolt for boilers having a tell-tale bore 2 and the latter may be made slightly conical at the inner end of the bolt, as indicated at 3.

40 Located within the inner end of the bore 2 is a tube 4 having a hole 5 at its inner end. The other end of said tube may be somewhat enlarged and made conical as at 6 to fit the conical end portion of the bore 2. The tube 4 is preferably made of non-magnetic material and contains a bar or piece 45 of iron 7 which is normally embedded in a body of soluble material 8 (such as salt) and is normally held immovably thereby. The open end of the tube 4 is closed by a 50 plug 9 (which may be made of a refractory element similar to clay) and the iron piece 7 is so disposed in the body of soluble ma-

terial 8 that it will be normally out of contact with said plug as well as with all parts of the interior surface of the tube.

55

If the pole of an electro-magnet 10 having its coil included in circuit with a source of alternating current supply, indicated diagrammatically at 11, be placed in proximity to the end of the staybolt, the iron 60 piece 7 would tend to be attracted by it but under normal conditions said iron piece will be held immovable by the soluble material 8 in which it is embedded. Should the bolt become ruptured and thus permit the entrance of moisture into the tell-tale bore 2, such moisture would enter the tube 4 through the hole 5 and dissolve the material 8, thus releasing the iron piece 7. Under such conditions the placing of the 70 magnet in proximity to the end of the bolt will cause the iron piece to rattle within the tube and thus afford an audible signal denoting the ruptured condition of the bolt.

75 Instead of forming the tube 4 with the plug portion 6 and providing a separate plug in the latter, we may provide a tube 12 cylindrical from end to end and a separate plug 13 which serves to close the bore 2 and also the end of said cylindrical tube, 80 as shown in Fig. 3.

Having fully described our invention what we claim and desire to secure by Letters-Patent, is:

1. The combination with a staybolt having 85 a tell-tale bore, of soluble material in said bore, and an iron piece normally held fixed by said soluble material and adapted when said material shall have been dissolved by the entrance of moisture into the tell-tale 90 hole, to be moved by the application of an electro-magnet having its coil included in an alternating current source of electrical supply to provide an audible signal denoting a ruptured condition of the bolt. 95

2. The combination with a staybolt having a tell-tale bore, of a non-magnetic tube located within said bore and having an entrance opening for moisture, soluble material in said tube, an iron piece normally embedded in said soluble material, and a closure for said tube. 100

3. The combination with a staybolt having a tell-tale bore, of a tube therein hav-

ing a hole at one end, and a plug portion at the other end located in the entrance of said tell-tale bore, a plug closing the end of the tube, soluble material inclosed within said tube, and an iron piece normally embedded in said soluble material and out of engagement with the walls of the tube.

5 In testimony whereof, we have signed this

specification in the presence of two subscribing witnesses.

JOHN ROGERS FLANNERY.
ETHAN I. DODDS.
